UNITED STATES PATENT OFFICE.

JOHN HAYS HAMMOND, JR., OF GLOUCESTER, MASSACHUSETTS.

TOY LOCOMOTIVE.

Application filed January 6, 1920, Serial No. 349,801. Renewed February 23, 1924.

To all whom it may concern:

Be it known that I, JOHN HAYS HAMMOND, Jr., a citizen of the United States, and a resident of Gloucester, county of Essex, and 5 State of Massachusetts, have invented certain new and useful Improvements in Toy Locomotives, of which the following is a specification.

Some of the objects of the present invention are to provide means for automatically changing the speed of a moving body; to provide mechanism whereby the speed of a moving body may be changed at a predetermined point or points; to provide means for 10 automatically shifting a gear transmission from high to low speed when a moving body ascends or is about to ascend an incline; to provide means for automatically shifting a gear transmission from low to high speed 15 when a moving body reaches a level after ascending an incline; and to provide other improvements as will hereinafter appear.

In the accompanying drawings Fig. 1 represents a miniature railway equipped with 25 the apparatus embodying the present invention; Fig. 2 represents a transverse section of a locomotive and track showing one form of the present invention; Fig. 3 represents a plan of one form of track equipment employed with the present invention; and Fig. 30 Fig. 4 represents a section on line 4—4 of Fig. 2. Fig. 5 is a section taken on the line 5—5 of Fig. 3; and Fig. 6 is a section taken on the line 6—6 of Fig. 3.

Referring to the drawings, a locomotive 10 or other suitable body arranged to be propelled under its own power is shown mounted upon a track 11 which includes in its length an upwardly inclined portion 12 in 35 order to direct the locomotive 10 to a new level 13. In the present form of the invention it is preferred to consider the device as a toy railroad and the track 11 is arranged to simulate an ordinary railroad track having 40 different levels caused by hills or the natural irregularities of the land.

In order to propel the locomotive 10 it is equipped with driven wheels 14 running respectively upon rails 15 and driven through 45 the medium of an axle 16 which is common to both of the wheels 14, and suitably geared to a source of power such as a motor 17, of any suitable type.

For transmitting power from the motor 17 50 to the axle 16, the motor 17 has a driving shaft 20, keyed to which is a gear 21 in mesh

with a gear 22 fast to a countershaft 23 which is rotatably mounted at opposite ends in the wheel truck frame 24. This countershaft 23 has fixed thereto a gear 25 arranged 60 to mesh with a gear 26 which is mechanically connected to transmit motion to the axle 16.

For the purpose of changing the speed of the axle 16 according to requirements, such as to produce high speed under normal track 65 conditions and slow speed under conditions where a maximum energy is necessary, the gear 26 is fast to a sleeve 30 which is slidably mounted on the axle 16 but prevented from relative turning action by a key 31 arranged 70 in the usual manner. This sleeve 30 also carries a gear 32 fast thereon having a diameter preferably greater than the diameter of the gear 26 and in mesh with a gear 33 fast to the countershaft 23. The gear 33 is preferably 75 of less diameter than the gear 25 while the axial distance between the gears 25 and 33 is different from the distance, axially considered, of the gears 26 and 32. The arrangement is such that when the sleeve 30 is 80 in one operative position the gears 25 and 26 are in mesh and the gears 32 and 33 are out of mesh, while in the second operative position of the sleeve 30 the gears 25 and 26 are 85 out of mesh and the gears 32 and 33 are in mesh. Thus when the gears 25 and 26 are in mesh the high speed transmission will be effective and when the gears 32 and 33 are in mesh the low speed transmission will be effective.

In order to shift the sleeve 30 from high speed position to low speed position and vice versa, it is provided with a circumferentially slotted part 34 arranged to receive the bifurcated end 35 of a lever 36 which is 90 pivoted intermediate its ends as indicated at 37 to the frame 24. The construction is such that the lever 36 has a free end or arm 40 extending toward the track 11 and terminating in relatively close proximity thereto. 100 Thus by shifting the lever 36 in one direction or the other about its pivot 37, the sleeve 30 is moved in the desired manner.

For holding the lever 36 in either of its shifted positions the arm 40 passes, in the 105 present instance, between two spaced members 41 of spring material which are properly located to frictionally hold the arm 40 through the medium of hangers 42 suspended from the frame 24. The spring or clip members 41 are suitably shaped to provide seats for the arm 40, in either of which

it is substantially locked until a change of position is required.

As a means to automatically shift the arm 40 to change the speed of the moving body 5 one or more curved ramp rails 43 may be employed each fixed to the track, in any well known manner, in the path of the arm 40. Each ramp rail 43 is preferably fixed to a bed plate 44 having downwardly turned 10 side flanges 45 of suitable spring material and are arranged to fit between the track rails 15 with a wedge action to hold the plate 44 firmly in position.

In order to prevent endwise movement of 15 the plate 44, due to the trip 40, striking a ramp rail 43, a plurality of transverse depending ribs 45 are provided which are properly spaced to interfit with the ties 46 or other cross pieces of the track structure.

20 For the purpose of equalizing the side thrust the car, caused by the trip 40 striking a ramp rail 43, there is a guard rail 47 fixed to the plate 44 in such close proximity to the side edge as to form an abutment parallel to one track rail 15 with sufficient clearance for the wheel flange to pass freely. As a result any side thrust transmitted to the car, by the action of the ramp rail 43 shifting the trip 40, is taken up by the 25 guard rail 47 and the danger of the car leaving the track is eliminated.

From the foregoing it will be evident that the ramp rail structure is removable and each plate 44 may be taken up and placed at 30 any desired place to change the speed of the moving vehicle. Thus at the bottom of a grade, one of the ramp rails 43 may be positioned to cause the gears to be shifted to low speed, while another ramp rail 43 may be placed at the top of the incline to restore the gears to high speed. In case of a curve 35 the ramp rails 43 may be placed as desired at the beginning and end of the curve to give a slow speed on the curve and a return to high speed after the curve is passed. Further the ramp rail structure is reversible so that it can be used for either direction of travel of the car.

Although only one of the many forms in 40 which this invention may be embodied has been shown herein, it is to be understood that the invention is not limited to any specific construction, but might be applied in various forms without departing from the 45 spirit of the invention or the scope of the appended claims.

Having thus fully described my invention, I claim and desire to protect by Letters Patent:

60 1. In a toy, the combination of a movable body, a track therefor, means to propel said body along said track, and means including a track device for mechanically changing the speed of said propelling means.

65 2. In a toy, the combination of a movable

body, a track therefor, means including a high gear mechanism and a low gear mechanism for propelling said body along said track, and means automatically operable to shift said propelling means from one gear 70 mechanism to the other gear mechanism.

3. In a toy, the combination of a movable body, a track therefor, means including a two speed mechanism for propelling said body along said track, means for changing 75 said propelling means from one speed to another, and means secured to said track for operating said speed changing means.

4. In a toy, the combination of a movable body, a track therefor, means including a variable speed mechanism for propelling said body along said track, a sleeve slidably mounted and arranged to control said speed mechanism, a lever connected to said sleeve, and means located on said track in the path 85 of said lever for changing said variable speed mechanism from one speed to another.

5. In a toy, the combination of a movable body, a track therefor, means including a high gear mechanism and a low gear mechanism 90 for propelling said body along said track, means to shift said propelling means from one speed to another, and a plurality of means fixed to said track for respectively operating said shifting means from high speed to low speed and from low speed to high speed.

6. In a toy, the combination of a movable body, a track therefor, means including a high gear mechanism and a low gear mechanism 95 for respectively propelling said body along said track, a trip arranged to shift said propelling means from one speed to another, and a plurality of ramp rails arranged to be removably secured to said track 105 in the path of movement of said track.

7. In a toy, the combination of a movable body, a track therefor, means including a high gear mechanism and a low gear mechanism 110 for respectively propelling said body along said track, a trip arranged to shift said propelling means from one speed to another, a plurality of ramp rails arranged to be removably secured to said track in the path of movement of said track, and means to prevent said body jumping the track through lateral thrust of said trip.

8. In a toy, the combination of a pair of track rails, a plate arranged to fit between said track rails, a ramp rail fixed to said plate, and means to removably secure said plate in operative position between said rails.

9. In a toy, the combination of a pair of track rails, a plate arranged to fit between 125 said track rails, a ramp rail fixed to said plate, ties for said rails, means to removably secure said plate to said rails, and means to interlock said plate with said ties.

10. In a toy locomotive, the combination 130

of a movable body, a track therefor having an inclined portion, means including a high gear mechanism and a low gear mechanism for respectively propelling said body along said track, a trip arranged to shift said propelling means, a ramp rail at the bottom of said incline arranged to cooperate with said trip to change from the high gear to

the low gear mechanism, and a second ramp rail at the top of said incline to shift said trip to change said propelling means back to high gear. 10

Signed at New York, in the county of New York and State of New York, this 2 day of January 1920.

JOHN HAYS HAMMOND, Jr.
